Patented June 1, 1976

240,103

BANK OF LOCKERS FOR BICYCLES, MOTORCYCLES OR THE LIKE

Benjamin Agundez III, 5930 Franklin,
Los Angeles, Calif. 90028

Filed Oct. 29, 1974, Ser. No. 518,320

Term of patent 14 years

Int. Cl. D6—04

U.S. Cl. D6—157

FIG.1.

FIG.2.

FIG.3.

FIG.4.

FIG. 1 is a front elevational view of a bank of lockers for bicycles, motorcycles or the like showing my new design;

FIG. 2 is a rear elevational view;

FIG. 3 is a top plan view; and

FIG. 4 is a right side elevational view.

I claim:

The ornamental design for a bank of lockers for bicycles, motorcycles or the like, substantially as shown.
